UNITED STATES PATENT OFFICE.

LAZARD KAHN AND RUDOLPH THIEM, OF HAMILTON, OHIO, ASSIGNEES TO
F. & L. KAHN & BROTHERS, OF SAME PLACE.

DESIGN FOR A COOKING-STOVE.

SPECIFICATION forming part of Design No. 17,744, dated September 27, 1887.

Application filed August 2, 1887. Serial No. 245,984. Term of patent 7 years.

To all whom it may concern:

Be it known that we, LAZARD KAHN, a citizen of the United States, and RUDOLPH THIEM, a subject of the Emperor of Germany, both 5 residents of Hamilton, Butler county, Ohio, have invented certain new and useful Improvements in Designs for Stoves, of which the following is a specification, reference being had to the accompanying print, forming a part 10 hereof, which is a perspective view of a stove embodying our design.

The leading features by which our design is characterized are as follows:

15 The front door, A, is embellished by a central rectangular panel surrounded by an ovolو molding whose inner edge is perpendicular to the plane of the panel and whose outer edge slopes gradually to the outer edge of the door. The shadow effect just within this molding 20 strongly simulates an undercutting of the molding.

25 The smaller doors, B, are embellished by a central rectangular panel whose marginal lines converge and interlace at the center of the panel, the ends of the panel within the marginal lines being ornamented each with a leaf.

30 The skirting C is embellished by a lower marginal molding horizontal and straight at the center and terminating in curves concave below, the central face of the skirting being ornamented by a fanciful shield flanked by representations of ferns, and the ends of the skirting beyond the ferns being ornamented by foliate scrolls.

35 The legs D are embellished by edge marginal lines merging at the base of the legs into an upturned leaf against the face of the foot of the leg, the central face of the leg being ornamented by a conventional leaf having a central stem with spear-shaped side projections, the upper portion of the leg being ornamented by a central fanciful shield flanked by representations of fern-leaves.

40 The upper front door, E, is embellished by a marginal rope molding surrounding a panel ornamented by a central shield flanked by foliate work.

We claim—

45 1. The design for a stove herein shown and 50 described, comprising the oven-door A, em-

bellished by a central rectangular panel containing a circular central ornament flanked within said panel by foliate scrolls, said panel being surrounded by a molding retreating from the panel backwardly and outwardly to the 55 margin of the door, the outer member of said molding being a rope molding, while the inner member is ornamented by scrolls and leaves, each mitered corner of the molding being ornamented by a leaf reaching from the inner 60 member to the outer member thereof; the smaller doors, B, embellished by a central rectangular panel whose marginal lines converge and interlace at the center of the panel, the ends of the panel within the marginal lines being 65 ornamented each with a leaf; the skirting C, embellished by a lower marginal molding horizontal and straight at the center and terminating in curves concave below, the central face of the skirting being ornamented by 70 a fanciful shield flanked by representations of ferns, and the ends of the skirting beyond the ferns being ornamented by foliate scrolls; the legs D, embellished by edge marginal lines merging at the base of the legs into an up- 75 turned leaf against the face of the foot of the leg, the central face of the leg being ornamented by a conventional leaf having a central stem with spear-shaped side projections, the upper portion of the leg being ornamented by a central 80 fanciful shield flanked by representations of fern-leaves, and the upper front door, E, embellished by a marginal rope-molding surrounding a panel ornamented by a central shield flanked by foliate work. 85

2. In a design for a stove, a door embellished by a central rectangular panel surrounded by an ovolو molding whose inner edge is perpendicular to the plane of the panel and whose outer edge slopes gradually 90 to the outer edge of the door, as described and shown.

3. In a design for a stove, the smaller doors, B, embellished by a central rectangular panel whose marginal lines converge and interlace 95 at the center of the panel, the ends of the panel within the marginal lines being ornamented each with a leaf, as shown.

4. In a design for a stove, the skirting C, embellished by a lower marginal molding hori- 100

zontal and straight at the center and terminating in curves concave below, the central face of the skirting being ornamented by a fanciful shield flanked by representations of ferns, 5 and the ends of the skirting beyond the ferns being ornamented by foliate scrolls, as shown.

5. In a design for a stove, the legs D, embellished by edge marginal lines merging at the base of the legs into an upturned leaf against 10 the face of the foot of the leg, the central face of the leg being ornamented by a conventional

leaf having a central stem with spear-shaped side projections, the upper portion of the leg being ornamented by a central fanciful shield flanked by representations of fern-leaves, as 15 shown.

LAZARD KAHN,
RUDOLPH THIEM.
